FIG. 1

FIG. 2

FIG. 3

FIG. 4

INVENTOR.
RUDOLF JACOBI
BY A.B. Bowman
ATTORNEY

UNITED STATES PATENT OFFICE.

RUDOLF JACOBI, OF SAN DIEGO, CALIFORNIA.

WALL OR RECESS BED.

Application filed April 21, 1921. Serial No. 463,380.

To all whom it may concern:

Be it known that I, RUDOLF JACOBI, a citizen of the United States, residing at San Diego, in the county of San Diego and State 5 of California, have invented a certain new and useful Wall or Recess Bed, of which the following is a specification.

My invention relates to a wall or recess bed, which may be positioned in a recess in 10 a wall of a room or may be covered with a curtain in a room as desired. The objects of my invention are; first, to provide a bed of this class which may be turned into a vertical position when not in use in which 15 position it occupies very little space on the floor of the room or very little recess space in the wall; second, to provide a novelly constructed wall bed structure of this class; third, to provide a novel means for supporting 20 said bed in a vertical position when not in use; fourth to provide a bed structure of this class in which an ordinary bed frame may be utilized with means in connection therewith for moving it from a horizontal 25 to a vertical position and from a vertical to a horizontal position and supporting it in either of such positions, and fifth, to provide a bed of this class which is very simple and economical of construction, durable, 30 easy to operate, easy to install and which will not readily deteriorate or get out of order.

With these and other objects in view as will appear hereinafter my invention consists of certain novel features of construction, combination, and arrangement of parts 35 and portions as will be hereinafter described in detail and particularly set forth in the appended claims, reference being had to the 40 accompanying drawings and to the characters of reference thereon, which form a part of this application, in which:—

Figure 1, is a sectional plan view of a wall with a recess therein showing my bed 45 in its vertical position as positioned therein when not in use. Fig. 2, is an elevational view of the bed in its vertical position showing the side facing the room, and showing portions broken away at one end to facilitate the illustration. Fig. 3, is an end elevational view thereof, and showing the support 5 in its supporting position by dotted lines, and Fig. 4, is an end elevational view 50 of the bed when in a horizontal position, and down ready for use.

Similar characters of reference refer to

similar parts and portions throughout the several views of the drawings.

The bed spring frame 1, including the side and end frames and springs is of the ordinary or conventional type. The end members 2, upright supports 3, stop members 4, hinged supports 5, braces 6, supporting legs 7, braces 8 and connecting rod 9, constitute the principal parts and portions of my bed 65 structure.

The end members 2, are secured to the end of the conventional bed spring frame, and these members are pivotally mounted intermediate their ends preferably nearer one 70 end than the other on the uprights 3, by means of L shaped pipe members 9^a, which extend through said end members 2 and the member 3. This member 9^a, extends downwardly and connects with a main pipe 9, by means of T members 9^b, which rods 9 and members 9^a and 9^b forms the support for the uprights 3 and hold them in proper relation to each other. These uprights 3 are mounted on casters 3^a which facilitates their 75 movement on the floor. Hinged to the front sides of the supports 3, are the supporting members 5, which are of considerable length and on the lower sides of their extended ends are mounted casters 5^a. Pivotally mounted 80 on each of these supports 5 is a brace member 6, which is provided with a notch 6^a in its one end and is adapted to engage a staple member 3^b in the support 3 bracing the support 3 relatively to the support 5, and in 85 such position permitting the bed to be raised at its outer end with the movement of the member 6 so that latch 6^a is disengaged. Pivotally mounted on these end members 2 are also the supporting legs 7, by means of 90 the braces 8. These members 7 will swing into position when the frame is let down, as shown best in Fig. 4 of the drawings, for supporting the bed when down and rest against the frame when up in a vertical position as shown in Fig. 3. The members 2 are each provided in one end with a caster 2^a which are adapted to roll against the wall with the moving of the bed from the horizontal to the vertical position. Secured to 95 the floor a short distance from the wall, are the stop members 4, which are adapted to engage the lower extending portion 1^a of the spring frame 1, so that when it is desired to move the bed from the vertical position to 100 the horizontal position for use, the operator releases the member 5 letting it down as

105
110

shown in Fig. 4, so that the notch 6^a engages the keeper 3^b when moved outwardly. The bed frame engages the stop member 4 which tilts said frame so that its one edge 5 swings against the wall so that the casters 2^a engage the wall in its movement and retards the pivotal movement of the frame relative to the supports 3 so that it gradually turns down into a horizontal position.

10 The leg member 7 assuming its proper position and may be braced by the brace 8 if desired. In re-positioning the bed in a vertical position the operator grasps the frame at the outside pushes it against the wall 15 and raises it at the same time the supports 3 are moving inwardly. The casters 2^a engage the side wall and the bed assumes a vertical position. The movement being caused by pushing the frame work toward the wall 20 with the casters 2^a against the wall and the side rail 1^a resting against the inner side of stops. The leg members 7 drop down 25 against the bed when in vertical position and the members 5 may be raised up against the bed by releasing the brace member 6 from the keeper 3^b and letting the brace member pass through said keeper.

Though I have shown and described a particular construction, combination and arrangement of parts and portions I do not wish to be limited to this particular construction, combination and arrangement but desire to include in the purview of my invention the construction, combination and arrangement substantially as set forth in the appended claims.

It is obvious that with this construction there is provided a bed frame, consisting of the ordinary bed spring frame and provided with means for pivotally supporting it upon a longitudinal axis intermediate its sides so that it may be tilted in a vertical position on said support or let down in a horizontal position for use; that the movement from the vertical to the horizontal position is retarded so that it moves in a slow, orderly manner by means of the rollers 2^a against the wall, and at the same time moving the carriage outwardly by the pressure 45 against the wall, but when it assumes a horizontal position the leg members 7, support the long end and the supports 3 are braced by means of the supports 5 and braces 6. The stop members 4 on the floor 50 engaging the side rail 1^a of the frame causes the pivotal movement with the movement of the bed outwardly.

Having thus described my invention what

I claim as new and desire to secure by Letters Patent, is—

1. A bed of the class described adapted to be shifted to a vertical position adjacent a wall, including a spring frame, supports upon which said frame is pivotally mounted at its opposite ends intermediate its sides, 65 and provided with rollers to facilitate the movement of said supports, stop members positioned a short distance from the wall adapted to engage the one side rail of the spring frame for tilting the same with the 70 outward movement of the supports on the floor and means adapted to engage the wall of the room for retarding the movement of said frame on its pivotal mounting.

2. A bed of the class described adapted to 75 be shifted to a vertical position adjacent a wall, including a spring frame, supports upon which said frame is pivotally mounted at its opposite ends intermediate its sides, and provided with rollers to facilitate the 80 movement of said support, stop members positioned a short distance from the wall adapted to engage the one side rail of the spring frame for tilting the same with the outward movement of the supports on the 85 floor, means adapted to engage the wall of the room for retarding the movement of said frame on its pivotal mounting, and means hinged to said support adapted to extend into the room for bracing and sustaining 90 said supports and supporting the free side of the spring frame thereon.

3. A bed of the class described adapted to be shifted to a vertical position adjacent a wall, including a spring frame, movable 95 supports upon which said frame is pivotally mounted, and stop members positioned a short distance from the wall, adapted to engage one side of the spring frame for tilting the same with the outward movement of 100 the supports.

4. A bed of the class described adapted to be shifted to a vertical position adjacent a wall, including a spring frame, movable supports upon which said frame is pivotally mounted, stop members positioned a short distance from the wall, adapted to engage one side of the spring frame for tilting the same with the outward movement of the supports, and means adapted to engage 105 the wall of the room for retarding the pivotal movement of said frame.

In testimony whereof, I have hereunto set my hand at San Diego, California, this 15th day of April, 1921.

RUDOLF JACOBI.
